UNITED STATES PATENT OFFICE.

FRANK S. VERBECK, OF CHICAGO, ILLINOIS.

DESIGN FOR A LAMP-SHADE.

No. 39,285.

Specification for Design.

Patented April 28, 1908.

Application filed March 23, 1908. Serial No. 422,811. Term of patent 7 years.

To all whom it may concern:

Be it known that I, FRANK S. VERBECK, a citizen of the United States, residing at Chicago, in the county of Cook and State of Illinois, have invented a certain new, original, and ornamental Design for Lamp-Shades, of which the following is a specification, reference being had to the accompanying drawing, forming a part thereof.

Figure 1 is a perspective view of a lamp shade showing my new design; and Fig. 2 is a plan view of the lamp shade.

I claim:

The ornamental design for a lamp shade, as shown.

FRANK S. VERBECK.
